UNITED STATES PATENT OFFICE.

FRED H. KNAPP AND CLARENCE W. BLACKSTONE, OF CHICAGO,
ILLINOIS.

LABELING-MACHINE.

SPECIFICATION forming part of Letters Patent No. 761,080, dated May 31, 1904.

Application filed May 12, 1900. Serial No. 16,434. (No model.)

To all whom it may concern:

Be it known that we, FRED H. KNAPP and CLARENCE W. BLACKSTONE, citizens of the United States, residing at Chicago, in the county of Cook, State of Illinois, have invented certain new and useful Improvements in Labeling-Machines; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to can-labeling machines; and it consists in the construction and arrangement of parts hereinafter fully set forth, and pointed out particularly in the claims.

The object of the invention is to produce a machine of the character described in which the arrangement is such as to provide for applying paste to the lap end of the label as the can passes through the machine, so that said lap end will be firmly pasted down when the operation of applying the label to the can has been completed; to provide for spacing the cans upon their entrance into the machine, so as to prevent them from crowding against one another in their passage therethrough and interfere with the operation of labeling; to provide for feeding the can by gravity or momentum over a portion of the label-receptacle to obviate the buckling of the labels therein in advance of the can, and to provide for adjusting the lap-pasting device so as to insure a perfect operation thereof with labels of various lengths.

The object of the invention is attained by the mechanism illustrated in the accompanying drawings, in which—

Figure 1 is a side elevation of a machine embodying this invention. Fig. 2 is a plan view of a portion of the runway and label-receptacle, showing the vibratory plate crossing the label-receptacle, which serves to form a loop in the labels as they wind onto the cans, and thereby cause the pasted surface of the can to encounter the lap end of the label and apply

paste thereto as the can passes through the machine. Fig. 3 is a longitudinal section through the label-receptacle and can-conveying means as on line 3 3 of Fig. 2. Fig. 4 is a like view showing a can passing through the machine with a label partially attached thereto and a loop formed in said label by the oscillatory plate, whereby the label is taken up in length sufficiently to bring its lap end into contact with the paste previously deposited upon the can. Fig. 5 is a plan view in detail of the spacing device located at the feed end of the machine, whereby the cans are so spaced as to prevent more than one can from occupying the label-receptacle at a time.

Referring to the characters of reference, 1 designates the frame of the machine, which may be of any suitable construction. Supported in the machine is a can-runway 2, having a feeding-chute 3 communicating therewith. Over the can-runway and parallel therewith are traveling belts 4, which serve to convey the cans through the machine, said conveying-belts being driven through a crank 5 or any other suitable source of power connected by gear-wheels 6 and 7 with the shaft 75 of the pulleys carrying said belts.

Located in the can-runway and forming a portion thereof is a label-receptacle 8, adapted to contain the labels, which are applied to the can as they pass through the machine, and having a vertically-movable bottom 9, upon which said labels rest and by means of which they are carried upward to the cans as fast as they are consumed by the operation of labeling. The bottom of the label-receptacle is raised through the medium of a rack-bar 10, attached thereto and engaged by the toothed head 11 of the weighted lever 12, through the medium of which an upward pressure is exerted to hold the labels against the detaining-knives 13, which project into said receptacle from opposite sides and maintain the uppermost label therein on a plane with the runway of the can. At the same time said knives permit the cans as they pass in succession through the machine to pick up the uppermost label in the receptacle by contact of the pasted surface of the can therewith and roll the label on

the can in a manner well understood in the art, said knives being slightly actuated to assist in cutting through the labels by means of the angle-levers 14, which are attached to the 5 shafts of said knives and extend into the path of the rolling cans, whereby a depression of said levers by contact with the cans imparts a slight oscillation to the knives. A spring 15 serves to raise the levers 14 after being 10 depressed by the passage of the can thereover.

In the art of labeling cans it is essential that paste be applied to the extreme lap end of the label in order that said lap end may be firmly pasted down when the operation of labeling 15 has been completed. In this machine the lap end of the label is pasted by causing it to come in contact with the paste, which is deposited upon a portion only of the surface of the can and which serves to pick up the initial end of 20 the label, as well as to paste the lap end thereof. The paste is applied to the surface of the can by means of a roller 16, (see Fig. 1,) journaled in a paste box or receptacle 17 and extending above the plane of the can-runway, so as to bring each can into contact therewith as it 25 passes through the machine. The paste-roller is so positioned with respect to the label-receptacle as to cause the pasted surface on the can to encounter the forward end of the top label in 30 the receptacle as the can is conveyed through the machine. The paste employed is sufficiently adhesive to pick up said label, causing it to wind onto the can as the can rolls along. The initial end of the label does not cover the entire portion of the pasted surface on the can, but leaves part of said pasted surface exposed for the purpose of applying paste to the lap end of the label when brought into contact 35 with said exposed pasted surface. It will be understood that the length of the label is greater than the circumference of the can and that if the label were simply rolled upon the can its lap end would receive no paste, for the reason that it would overreach the pasted 40 surface. To bring the lap end of the label into contact with the pasted surface of the can as the can passes through the machine, and thereby apply paste to said lap end, so as to cause it to firmly adhere, a transverse 45 plate 18 is employed which crosses the label-receptacle transversely. This plate is flat and lies upon the surface of the uppermost label, so that the can in passing through the machine rolls over said plate, which becomes 50 interposed between the label and can and makes a sufficient loop in the label, as shown at 19 in Fig. 4, to compensate for the difference between the length of the label and the diameter of the can and cause the pasted 55 surface 20 of the can to impinge upon the lap end of the label as the can passes from the label-receptacle, thereby applying paste thereto and enabling the lap end of the label to be thoroughly pasted down as the can continues 60 its course through the machine. The plate

18 is mounted upon rearwardly-extending arms 21, which are provided with laterally-extending ends 22, suitably journaled and environed by the coiled spring 23, whose tension is exerted to normally hold said plate 70 upon the surface of the labels. By pivoting the arms of said plate in the manner described said plate is allowed to swing upwardly as the label draws from under it and prevent a possible tearing of the label and the offering 75 of any undue resistance to the passage of the can through the machine, said springs returning said plate to its normal position after the passage of each succeeding can.

In referring to Figs. 1, 3, and 4, it will be 80 seen that the conveyer-belt 4 is raised, as at 24, over the forward end of the label-receptacle and the plate 18, the purpose of which is to permit the can to roll by gravity or momentum from the forward end of the label-receptacle onto the plate 18. The reason for this arrangement is that the can rolls directly onto the labels and if forced downward with pressure would cause the labels to buckle in advance of the rolling can and move their upper ends downward from the upper end of said receptacle, thereby displacing them in the receptacle and preventing their proper application to the can.

To more perfectly illustrate the operation 95 of the swinging plate 18 and to describe its function, we will explain more fully the passage of the can across the label-receptacle. As the can enters the label-receptacle, as shown in Fig. 3, its position is such that the pasted 100 surface 20 thereon impinges upon the end of the label and causes the label to adhere thereto. Upon the entrance of the can into the receptacle it passes free from the conveying-belt 4 and rolls by gravity and its own momentum across said receptacle and winds the label thereon. As the can rolls onto the plate 18 the label draws taut from the upper edge of said plate, thereby momentarily arresting the rotation of the can and causing its lower 110 side to slide forward on said plate, thereby forming a loop 19 in the label by reason of said plate occupying the space between the label and can. This sliding movement of the can while the label is held by said plate 115 carries the can along such distance as to present its exposed pasted surface 20 in position to encounter the lap end of the label and at the same time brings said can again into contact with the conveyer-belt, when said can is again 120 forcibly rotated and is caused to draw upon the label with sufficient force to swing the plate 18 upward against the action of the springs 23 and carry the pasted surface of the can onto the lap end of the label. As the can 125 rolls from the end of the label it is released, when the spring 23 will carry the plate 18 downward onto the surface of the succeeding label, permitting the can to pass onward through the machine and roll the label there- 130

on, whose lap end is thereby firmly pasted down and the operation of attaching the label is completed. It will be understood that the width of the plate 18 determines the size of the loop formed in the label, and in order to vary the length of said loop according to the lap of the labels and compensate for the variation in the length thereof said plate is made adjustable in width by forming it in two parts, 10 consisting of the movable part 18 and the fixed part 25, to which the arms 21 are attached and which is provided with slotted ears 26, which extend onto the face of the part 18 and are adjustably attached there by screw-bolts 27, which pass through the slots of said ears and into the part 18, whereby by loosening said bolts the movable part 18 of said plate may be adjusted laterally with respect to the part 25, so as to increase or decrease 20 the width of said plate. As the cans (indicated by dotted lines 28) leave the runway and enter upon the label-receptacle they pass from the guiding-rails 29 of said way and are without anything to direct their course in 25 their passage over the label-receptacle excepting the flanged guide-plate 30, mounted upon the upper face of the plate 18, which is located in the path of the cans and which serves to right the cans as they pass between them and 30 cause said cans to pass over the plate parallel therewith, thereby insuring the winding of the labels straight upon the can. To prevent the crowding of the cans in their passage through the machine, so as to interfere with the operation 35 of the swinging plate 18, said cans are spaced upon their entrance into the machine by means of a spacing device mounted on the chute 3. This device consists of a rectangular frame 31, which describes a parallelogram and 40 is pivoted at its ends to uprights 32 and adapted to rock upon said uprights. A connecting-rod 33 is pivoted to one side of said frame at one end, and its opposite end is pivoted to a lever 34, which extends across the shaft 35 45 of one set of the feeding-pulleys and is pivoted at its rear end in the frame, as at 36. The lever 34 stands in the path of the cam (shown by dotted lines 37 in Fig. 1) mounted on the shaft 35 and which at each revolution 50 of said shaft engages said lever and raises the upper end thereof, thereby tilting or rocking the rectangular frame 31. As the inner side of said frame is raised the outer or upper side

is depressed, as shown by dotted lines in Fig. 1, so that the can lying within said frame is released and permitted to pass into the machine, while the next succeeding can in the chute 3 is held from entering the machine until the succeeding operation of said tilting frame, whereby the cans are regularly spaced 60 and fed into the machine at such intervals as to prevent them from interfering with one another in their passage therethrough.

Having thus fully set forth this invention, what we claim as new, and desire to secure by Letters Patent, is—

1. In a can-labeling machine, the combination of the can-runway, and means for applying paste to the can, of a label-receptacle in said runway, a flat plate crossing the label-receptacle from side to side and positioned to become interposed between the label and can, guide-flanges on said plate to direct the can in its passage thereacross, said plate being of a width to support and maintain the can thereon and to form a loop when the label is wrapped around it of such length as to bring the lap end of the label into contact with the paste on the can.

2. In a can-labeling machine, the combination with the can-runway and can-pasting means, of a label-receptacle, a movable transverse plate crossing said receptacle in a manner to become interposed between the can and label as the label is rolled onto the can, said plate being of such width as to support and maintain the can and composed of two opposed parts adjustable laterally, one of said parts having guide-flanges which direct the can.

3. In a labeling-machine, the combination with the can-runway and the pasting device, of a label-receptacle in said runway, a thin plate crossing the label-receptacle and lying upon the uppermost label, said plate being of a width to support and maintain the can and form a part of the can-runway having guide-flanges upon its upper face adapted to direct the can in its course thereacross.

In testimony whereof we sign this specification in the presence of two witnesses.
